UNITED STATES PATENT OFFICE

HENRY H. TALBOYS, OF MILWAUKEE, WISCONSIN, ASSIGNOR TO NORDBERG MANUFACTURING CO., OF MILWAUKEE, WISCONSIN, A CORPORATION OF WISCONSIN

CUTTER HEAD AND BIT

Application filed June 29, 1931. Serial No. 547,479.

My invention relates to an improved cutter or cutter head and has for one purpose the provision of improved means for adjustably securing a cutter or a cutter head. 5 Another object is the provision of improved means for adjusting cutting elements. Other objects will appear from time to time in the course of the specification and claims.

I illustrate my invention more or less dia- 10 grammatically in the accompanying drawings, wherein

Figure 1 is an elevation of an adzing device to which my cutter head and cutter have been applied;

15 Figure 2 is a top plan view of the cutter head with cutters in place;

Figure 3 is a section on the line 3-3 of Figure 2;

20 Figure 4 is an enlargement of a portion of Figure 3;

Figure 5 is a section on the line 5-5 of Figure 4;

25 Figure 6 is a view of a cutter receiving member; and

Figure 7 is a view of an individual cutter.

Like parts are indicated by like symbols throughout the specification and drawings.

I have illustrated my invention as applied to an adzing machine but it will be realized 30 that this is but one of a number of applications which may be made of it.

Referring to the drawings, A indicates a railroad track tie carrying the rail A¹.

B indicates generally the transverse frame 35 of an adzing machine, upon which is mounted any suitable motor B¹ with a drive wheel B². B³ is a belt passing about the pulley B⁴ which rotates the shaft B⁵.

C is any suitable supporting wheel or 40 wheels upon which the transverse frame B is mounted. The rollers C¹ prevent lateral movement of the wheel C in relation to the rail A¹.

D indicates any suitable counter balance 45 or poise adapted to maintain the center of mass of the entire device along an axis generally aligned with a rail A¹. The operator may employ the handle D¹ to thrust the outer end of the frame downwardly but 50 preferably the weight D is sufficient to hold

the outer end of the frame B tilted upwardly away from the tie.

E generally indicates a cutter head mounted on the lower end of the shaft B⁵, and rotated in response to rotation of the drive 55 wheel B². The cutter head E may include the hub E¹, web portions E² and radial ribs E³ associated with the webs E². The webs E² are recessed or cut back as at E⁴ adjacent one face of each of the ribs E³. The ribs 60 E³ are somewhat thickened or strengthened as at E⁵. The exposed face of each such portion E⁵ is provided with a recess E⁶ adjacent its outer end and another recess E⁷ adjacent its inner end. 65

G indicates a cutter receiving abutment member fitted in the recess E⁶. Its longitudinal movement is prevented by the upper and lower flanges G¹. Its forward face is channelled as at G² to receive the longitudinally extending rib G⁴ of the cutter member G³. It will be seen, as in Figure 5, that the cutter member is of substantially greater length than the abutment G. 70

H indicates a clamped member having a 75 flange H¹ conforming and penetrating the aperture E⁷. At its opposite end or edge it is provided with a frame portion H² opposed to the outer face of the cutter G³. H³ indicates a lock bolt passing through the aperture H⁴ of the member E⁵. It is provided with a head H⁵ which engages the face of the member E⁵ opposite to the apertures E⁶ and E⁷. The bolt H³ also passes through an aperture H⁶ in the member H. Washers H⁷ 80 and a nut H⁸ may be employed to lock the parts in the position in which they are shown in Figures 4 and 5, with the lower cutting edge G¹⁰ of the cutter G³ in cutting position. The cutter is made reversible, 85 with cutting edges at top and bottom. When reversal is desired, or longitudinal shifting of the cutter G³, the nut H⁸ may be slackened and the cutter G³ moved or reversed.

It will be realized that whereas I have 90 described and shown a practical and operative device, nevertheless many changes may be made in size, shape, number and disposition of parts without departing from the spirit of my invention. I, therefore wish, 95 100

my drawings to be taken as in a broad sense illustrative and diagrammatic rather than as limiting me to the precise detail of the present showing.

5 The use and operation of my invention are as follows:

I illustrate the cutter head E, which, in the embodiment of my invention herein shown, is employed to adze railroad ties.

10 The head is rotated about a generally vertical axis, which, at the same time is moved along the track, thus adzing a flat bottomed depression to receive the base flange of the rail. The individual cutters G³ are preferably set to a uniform cutting plane perpendicular to the axis of rotation of the head. In adzing an old device it often happens that pieces of metal are left in the ties, such as the shanks of old railroad spikes.

15 The life of the individual cutter member is, therefore, short, and I wish to provide for quick and easy adjustment, reversal or replacement. In effect drawing up on the nut H⁸ rotates the clamp member H about an axis adjacent the engagement between the portion H¹ with the aperture or depression E⁷. The end H² is powerfully thrust against the cutter G³. The cutter is prevented from twisting by the rib G⁴ which 20 engages the abutment G. The abutment is positioned by the flanges G⁴ and is prevented from twisting by its seat in the depression E⁶. A relatively slight loosening of the nut H⁸ permits the cutter G³ to be slid up or 25 down or to be removed altogether for reversal or replacement. The abutment member G, however, is kept in place even when the cutter is removed from between it and the portion H² of the clamp member.

30 40 I claim:

1. In a cutter head, a rotatable head member disposed in a plane transversely of the axis of rotation of the head, and provided with a cutter receiving face portion 45 lying in a plane substantially parallel to the axis of rotation, said face portion being provided with radially spaced recesses extending substantially parallel to the axis of rotation, a cutter abutment positioned in one 50 of said recesses and restrained thereby from radial motion in either direction, and carrying parts interfitting with said head to hold the abutment against lateral and longitudinal movement with respect to the head, a 55 cutter member contacting the exposed face of the abutment, and extending transversely of the plane of the head substantially parallel to the axis of rotation thereof, the contacting faces of the cutter and abutment 60 being provided with longitudinally extending interfitting parts, a clamping member having a portion engaging the exposed face of the cutter to urge the cutter into engagement with the abutment, said clamping member carrying a flange seated in another of 65

said recesses in the face portion of the cutter head, and a bolt member penetrating the face portion of the cutter head and said clamping member intermediate said recesses for securely drawing said clamping member into engagement with the cutter whereby to retain the parts in operative position on the cutter head.

2. In a cutter head, a shaft and means for rotating it, a head member mounted on said shaft and lying in a plane generally perpendicular to the axis of rotation of said shaft, said head member being provided with radial surfaces generally parallel with the axis of rotation of the head, said surfaces being provided each with a pair of radially spaced depressions extending in general parallelism with said axis of rotation, an abutment member removably positioned in one of each said pairs of depressions, said abutment member being formed to interpenetrate therewith, means for preventing longitudinal movement of said abutment member in its depression, a cutter blade opposed to each said abutment member, cutter blade and abutment member being formed with interpenetrating parts, said interpenetrating parts lying in general parallelism with the axis of rotation of the cutter head, and radially extending clamp elements one end of each of which is opposed to one of said cutter members, and another end of which penetrates a radially spaced depression, and clamping means adapted to draw each said clamp element against its cutter member, said clamping means being positioned between said radially spaced pair of depressions.

3. In a cutter head, a shaft and means for rotating it, a head member mounted on said shaft and lying in a plane generally perpendicular to the axis of rotation of said shaft, said head member being provided with radial surfaces generally parallel with the axis of rotation of the head, said surfaces being provided each with a pair of radially spaced depressions extending in general parallelism with said axis of rotation, an abutment member removably positioned in one of each said pairs of depressions, said abutment member being formed to interpenetrate therewith, means for preventing longitudinal movement of said abutment member in its depression, a cutter blade opposed to each said abutment member, cutter blade and abutment member being formed with interpenetrating parts, said interpenetrating parts lying in general parallelism with the axis of rotation of the cutter head, and radially extending clamp elements one end of each of which is opposed to one of said cutter members, and another end of which penetrates a radially spaced depression, and clamping means adapted to draw each said clamp element against its cutter member,

said clamping means being positioned between said radially spaced pair of depressions, said cutter blades being positioned at various radial distances from the center of 5 rotation of the cutter head.

4. In a cutter head, a shaft and means for rotating it, a head member mounted on said shaft and lying in a plane generally perpendicular to the axis of rotation of said 10 shaft, said head member being provided with radial surfaces generally parallel with the axis of rotation of the head, said surfaces being provided each with a pair of radially spaced depressions extending in general 15 parallelism with said axis of rotation, an abutment member removably positioned in one of each said pairs of depressions, said abutment member being formed to interpenetrate therewith, means for preventing 20 longitudinal movement of said abutment member in its depression, a cutter blade opposed to each said abutment member, cutter blade and abutment member being formed with interpenetrating parts, said interpenetrating parts lying in general parallelism 25 with the axis of rotation of the cutter head, and radially extending clamp elements one end of each of which is opposed to one of said cutter members, and another end of 30 which penetrates a radially spaced depression, and clamping means adapted to draw each said clamp element against its cutter member, said clamping means being positioned between said radially spaced pair of 35 depressions, said cutter blades being provided with cutting edges generally perpendicular to the axis of rotation of the cutting head, said edges being positioned beneath the general plane of the lower face of the head 40 member.

5. In a cutter head, a shaft and means for rotating it, a head member mounted on said shaft and lying in a plane generally perpendicular to the axis of rotation of said 45 shaft, said head member being provided with radial surfaces generally parallel with the axis of rotation of the head, said surfaces being provided each with a pair of radially spaced depressions extending in general 50 parallelism with said axis of rotation, an abutment member removably positioned in one of each said pairs of depressions, said abutment member being formed to interpenetrate therewith, means for preventing 55 longitudinal movement of said abutment member in its depression, a cutter blade opposed to each said abutment member, cutter blade and abutment member being formed with interpenetrating parts, said interpenetrating parts lying in general parallelism 60 with the axis of rotation of the cutter head, and radially extending clamp elements one end of each of which is opposed to one of said cutter members, and another end of 65 which penetrates a radially spaced depression,

and clamping means adapted to draw each said clamp element against its cutter member, said clamping means being positioned between said radially spaced pair of depressions, some of said cutter blades being 70 provided with cutting edges generally parallel with the axis of rotation of the cutter head and extending outwardly beyond the periphery of the head member.

Signed at Milwaukee, county of Milwaukee and State of Wisconsin, this 19th day of June, 1931.

HENRY H. TALBOYS.
